(57) **CLAIM**

The ornamental design for a lid for a culture vessel, as shown and described.

DESCRIPTION

FIG. 1 is a front view of a lid for a culture vessel of the present invention.

FIG. 2 is a rear view of the lid for a culture vessel of FIG. 1.

FIG. 3 is a top plan view of the lid for a culture vessel of FIG. 1.

FIG. 4 is a bottom view of the lid for a culture vessel of FIG. 1.

FIG. 5 is a right side view of the lid for a culture vessel of FIG. 1.

FIG. 6 is a left side view of the lid for a culture vessel of FIG. 1.

FIG. 7 is a perspective view of the lid for a culture vessel of FIG. 1.

FIG. 8 is a sectional view of the lid for a culture vessel of FIG. 1, taken along the line 8-8 of FIG. 1; and,

FIG. 9 is an enlarged sectional view of the lid for a culture vessel of FIG. 1, taken along the line 9-9 of FIG. 8.

The features shown in dotted lines depict environmental subject matter only and form no part of the claimed design. The broken lines in the drawing adjacent to a shaded area of the lid for the culture vessel depict the boundary of the claim. It is understood that the claim extends to the boundary.

(Continued)

ary, but that the boundary forms no part of the claim. All other broken lines depict unclaimed portions of the lid for the culture vessel.

1 Claim, 9 Drawing Sheets
